UNITED STATES PATENT OFFICE.

AMBROSE TZIKA, OF CEDAR GROVE, WEST VIRGINIA, ASSIGNOR OF ONE-HALF TO
HENRY W. RAMSEY, OF CEDAR GROVE, WEST VIRGINIA.

AIR-PUMP-OPERATING DEVICE.

Application filed June 14, 1928. Serial No. 285,400.

The invention relates to air pumps used for inflating automobile tires, and for other purposes, and has for its principal object the provision of means by which operation of the 5 pump by hand may be dispensed with, and consists in the provision of means for operation of the pump piston by foot power.

A further object of the invention is the provision of an attachment for air pumps 10 providing means for operation of the pump by foot power, the attachment being collapsible so that the pump and operating mechanism may be conveniently transported and stored.

15 The invention will be described in detail hereinafter and will be found illustrated in the accompanying drawings in which

Figure 1 is a side view in elevation of an air pump showing the operating device applied thereto, the device being shown in collapsed position in full lines, and in extended, pumping position, in broken lines,

Figure 2 is a front view in elevation showing the pump in collapsed position,

25 Figure 3 is a transverse sectional view showing the pump operating mechanism,

Figure 4 is a transverse sectional view on a plane at right angles to the plane of the section of Figure 3,

30 Figure 5 is a horizontal sectional view on a plane indicated by the line 5-5 of Figure 1, and

Figure 6 is a fragmental detail of the air delivery tube.

35 In the drawings similar reference characters are used to designate corresponding parts throughout the several views.

The air pumps shown in the drawings are of conventional reciprocating type having a 40 pump barrel 1, with a reciprocating piston 2 in each barrel and piston rod 3, with an inlet duct 4 controlled by a valve 5, and the outlet 6 in which is the usual check valve (not shown), said air pumps being mounted on the base 7.

8 indicates a tubular member supported on the base 7 and 9 a tubular rod slidably mounted in the tubular member 8 and held normally in lowered position by means of a 45 contractile spring 10 terminally engaging the lower end of the tubular member 8 and the upper end of said rod. 11 indicates a handle secured to the upper end of the tubular rod

before raising it. The upper end of the tubular member 8 is provided with one or more 55 longitudinal slits 12 intersecting the upper edge of the tubular member, to permit collapsing of the upper end of the tubular member to clamp the tubular rod 9 in adjusted position by means of a screw clamp consisting of a strap 13 having projecting ends 14 through which is extended a bolt and nut 15 to draw the ends of the strap together and clamp the upper end of the tubular member in engagement with the rod 9 as stated. 60

The upper ends of the piston rods 3 are provided with T-couplings 16 through which an arm 17 is extended. Secured to the arm 17 between the T-couplings 16 is a plunger 18 that is U-shape in cross section as shown 70 in Figure 5, said plunger being secured to the arm 17 by means of an integral tongue 19 on the upper end of the plunger that is bent around the arm 17 and has its end secured by means of a bolt 20, 21 designating a bushing sleeve between said arm 17 and the secured tongue 19. Pivotal secured to the plunger 18 adjacent to its lower end, is a 75 pedal 22 having an offset portion 23 to receive the pivot pin 24, the plunger 18 being slotted as shown at 25 to receive the pivoted end of the pedal, and 26 designates an L-shaped shoe secured to the plunger by welding or any other suitable manner to reinforce the pedal 22 when in lowered position as 80 shown in full lines in the drawings. The plunger 22 is adapted to be raised as shown in broken lines in Figure 3 when the device is not in use. 27 designates a contractile coil spring terminally engaging a hook member 90 28 secured to the upper end of the rod 9, and engaging at its other end as shown at 29 the lower end of plunger 18, the function of the spring 27 being to normally raise the plunger 18 and with it the pistons 2, for the up stroke 95 of the pistons when the device is in the position indicated in broken lines in Figure 1, the down stroke of the pistons being effected by pressing downwardly on the pedal 22 with the foot of the operator. 30 indicates a guide 100 sleeve secured to the upper end of the plunger 18 and slidably engaging the rod 9, and 31 another guide sleeve secured to the plunger 18 adjacent to the slot 25 and slidably engaging the tubular member 8, the sleeve 30 105 by engaging the upper end of the tubular

end of the pedal, and 26 designates an L-shaped shoe secured to the plunger by welding or any other suitable manner to reinforce the pedal 22 when in lowered position as 85 shown in full lines in the drawings. The plunger 22 is adapted to be raised as shown in broken lines in Figure 3 when the device is not in use. 27 designates a contractile coil spring terminally engaging a hook member 90 28 secured to the upper end of the rod 9, and engaging at its other end as shown at 29 the lower end of plunger 18, the function of the spring 27 being to normally raise the plunger 18 and with it the pistons 2, for the up stroke 95 of the pistons when the device is in the position indicated in broken lines in Figure 1, the down stroke of the pistons being effected by pressing downwardly on the pedal 22 with the foot of the operator. 30 indicates a guide 100 sleeve secured to the upper end of the plunger 18 and slidably engaging the rod 9, and 31 another guide sleeve secured to the plunger 18 adjacent to the slot 25 and slidably engaging the tubular member 8, the sleeve 30 105 by engaging the upper end of the tubular

member 8 serving as to stop to limit the downstroke of the plunger, while the sleeve 31 by engaging the clamp strap 13 serves to limit the up stroke of the plunger under the 5 impulse of the spring 27.

The delivery tube for the air comprises a flexible tubular member 32 having a conventional delivery nozzle 33 secured thereto at one end and a V-shaped tubular member 10 34 engaged at its other end with flexible tubes 35 secured to the arms of the member 34 and adapted to be connected with the delivery nozzles of the pumps as shown.

While the device disclosed in the drawings 15 includes two pump members that are simultaneously actuated by the operating device, it will be apparent that the device may be applied to a single pump member or may be arranged to operate more than two pump 20 members.

What is claimed is:—

1. An air pump operating device, comprising a plunger adapted to be secured to the piston rod of an air pump, manually operated, means to move said plunger and piston rod downwardly, and resilient means to raise said members.

2. An air pump operating device, comprising a plunger adapted to be secured to the piston rod of an air pump, means including a resilient member to normally raise the plunger and piston rod, and a pedal secured to the plunger to move it and the piston rod against the resistance of said resilient member.

3. An air pump operating device, comprising a plunger adapted to be secured to the piston rod of an air pump, a rod mounted for adjustment relatively to the air pump, 40 resilient means connecting said rod and plunger to normally raise it, and means to

actuate the plunger against the resistance of the spring.

4. An air pump operating device, comprising an arm adapted to be secured to the 45 piston rod of an air pump, a rod adjustable in relation to the pump, a plunger secured to said arm, resilient means connecting said rod and plunger to raise the plunger, and means to actuate the plunger against said 50 resilient means.

5. An air pump operating device, comprising a base adapted to support an air pump, a tubular member supported on the base, a rod slidably mounted in said tubular member, a spring terminally engaging said rod and tubular member to hold the rod in lowered position, an arm secured to the piston rod of the air pump, a plunger secured to said arm, resilient means connecting said 55 rod and plunger to normally raise the plunger, and a pedal secured to said plunger for actuating it against the resistance of said 60 resilient means.

6. An air pump operating device, comprising a base adapted to support an air pump, a tubular member supported on the base, a tubular rod slidably mounted in said tubular member, a spring terminally engaging the tubular member and the tubular rod, means to hold said rod in extended position 65 relatively to the tubular member and against the resistance of said spring, an arm secured to the piston rod of the air pump, a plunger secured to said arm, a spring terminally engaging the rod and plunger to normally raise it, a pedal secured to the plunger to 70 actuate it against said spring, and guide means secured to said plunger and slidably engaging the rod and tubular member.

In testimony whereof I affix my signature.
AMBROSE TZIKA.
